(57) CLAIM

The ornamental design for a reusable menstrual pad, as shown and described herein.

DESCRIPTION

FIG. 1 is a top view of an embodiment of a reusable menstrual pad in an open position.

FIG. 2 is a first bottom view of an embodiment of a reusable menstrual pad in an open position.

FIG. 3 is a second bottom view of an embodiment of a reusable menstrual pad in an open position.

FIG. 4 is a perspective view of the bottom side of an embodiment of a reusable menstrual pad in a closed position.

FIG. 5 is an exploded perspective view of the top side of an embodiment of a reusable menstrual pad in a closed position with a reusable liner insert.

FIG. 6 is a second perspective view of the top side of an embodiment of a reusable menstrual pad in a closed position with a reusable liner insert.

FIG. 7 is a second exploded perspective view of the top side of an embodiment of a reusable menstrual pad in a closed position with a reusable liner insert.

FIG. 8 is a third perspective view of the top side of an embodiment of a reusable menstrual pad in a closed position with a reusable liner insert.

FIG. 9 is a fourth perspective view showing an embodiment of a reusable menstrual pad in a closed position in one potential environment.

FIG. 10 is a first side view of an embodiment of a reusable menstrual pad in an open position.

FIG. 11 is a second side view of an embodiment of a reusable menstrual pad in an open position.

FIG. 12 is a third side view of an embodiment of a reusable menstrual pad in an open position; and,

FIG. 13 is a fourth side view of an embodiment of a reusable menstrual pad in an open position.

The regularly spaced broken lines along the perimeter of the reusable menstrual pad in FIGS. 1-5, 7, and 9 represent illustrative stitching and form no part of the claimed design. The remaining broken lines are for illustrative purposes only and form no part of the claimed design. The top view figure (FIG. 1) can be combined with the bottom view figures (FIGS. 2 and 3).
